UNITED STATES PATENT OFFICE.

FREDERICK EGGE, OF BRIDGEPORT, CONNECTICUT, ASSIGNOR TO THE SMITH & EGGE MANUFACTURING COMPANY, OF SAME PLACE.

LOCK.

SPECIFICATION forming part of Letters Patent No. 246,605, dated September 6, 1881.

Application filed February 10, 1881. (Model.)

To all whom it may concern:

Be it known that I, FREDERICK EGGE, of Bridgeport, in the county of Fairfield and State of Connecticut, have invented certain new and useful Improvements in Tumbler-Locks; and I do hereby declare that the following is a full and exact description thereof, reference being had to the accompanying drawings, making a part of this application.

10 My invention relates to locks, more especially that class of locks known as "tumbler-locks."

It has for its object to present a lock in which the action of the tumblers does not depend on 15 springs, the former being brought into proper position by the positive action of the key and unset by a rib on a tubular guide, and also to improve that class of keys which cannot be inserted into the lock except in the position 20 necessary to operate the same; and with these ends in view my invention consists in so arranging a series of tumblers in a lock that they shall be operated upon by the key alone to set the same, and without the intervention of 25 springs, and by a longitudinal rib on a tubular key-guide to unset the same, as will be herein-after more fully set forth.

It further consists in a flat key provided with a lip formed by cutting the end of the key transversely a short distance and turning up a short 30 stump, and providing a corresponding opening in the wall of the key-hole, whereby it is impossible to put the key in the wrong way.

In order that those skilled may fully understand my invention, I will describe its construction and mode of operation, reference being had by letters to the accompanying drawings, which represent my invention as applied to a 35 spring-latch, and in which—

40 Figure 1 is an internal view of the shell of my lock with the tumblers removed and exposing the spring-latch. Fig. 2 is a top view of the lock with the cover removed and the tumblers brought into position by the key, so as to bring the several slots in said tumblers in line, for the purpose hereinafter fully explained. Fig. 3 is a similar view of the same with the bolt partly withdrawn and its shoulder or stump part way within the coinciding 45 slots in the ends of the tumblers. Fig. 4 shows

the bolt locked against retraction. Fig. 5 is a view of my improved key, showing the peculiar arrangement of notches or slots on the side, and also the lip or guard on the end.

Similar letters indicate like parts in the several figures.

In all locks with which I am familiar the tumblers are either operated conjointly by the key and a series of springs, or else the tumblers are operated by gravity. In either case 60 the action of the tumblers depending on the springs or gravity after a short time becomes irregular and imperfect.

My invention is designed to overcome all the disadvantages incident to locks constructed as 65 above described, and has for its objects simplicity and economy of construction and accuracy and durability in operation.

In the accompanying drawings, A represents the case of the lock, and B the cover or face-plate. Within the case A is arranged a sliding latch, C, forced outwardly by a spring, D, and adapted to be drawn back by a knob, E. The longitudinal bar F of the latch is provided with a vertical slot, G, against the rear shoulder of which a projection on the bolt-plate 75 strikes to withdraw the latch, as will be presently explained.

K is a hub, having a radial arm, L, and a bearing, which fits in the plate B and extends through said plate a short distance. Through this hub K, and fastened to it so that both pieces revolve together, is the tubular guide I, through which the key passes, made to conform in shape and size to the key, and having formed on one side a longitudinal rib, I'', which, when the key is turned to withdraw it from the lock, acts upon one side of the central slots of the tumblers to disarrange or unset the same. The end I' of this tubular guide 90 is also a journal, and has its bearing in the back plate of the case. I then fasten in the escutcheon over that part of the hub K which extends through the plate B, either by drawing it on or in any other suitable manner. I 95 let the tubular guide I extend through the hub K more or less, according to the thickness of material in which the lock is to be placed, and use an escutcheon of more or less length accordingly. The tubular guide is cut away on 100

the inside of the case and the key is there exposed, as clearly shown in a detail figure in the drawings, (marked Fig. 3^a,) for the purpose hereinafter explained.

- 5 M is the tumbler-post, arranged near one end of the plate B, and over which all of the tumblers are passed, and on which they are all vibrated.
- 10 N are the tumblers, (the number being immaterial,) which are simple pieces of flat metal with a hole at one end to fit over the post M, and the other end slotted, as clearly shown, to permit the entrance of an upwardly-projecting shoulder or stump, O, turned up from one side 15 of the bolt-plate P. This bolt-plate P has a central opening, Q, behind the shoulder or stump O, to permit the rotation of the hub K, and with a shoulder, R, on one side, against which the radial arm L comes in contact to retract 20 the bolt-plate. There is, of course, a longitudinal channel in the plate P through which the post M passes, and which permits of the longitudinal reciprocation of the said plate, as clearly shown by dotted lines in Fig. 2.
- 25 S is a small projection or arm turned up from one side of the plate P, and is designed to fit within the slot G in the spring-latch bar F to draw back the same when the key is turned in the lock and the bolt retracted. The latter is 30 forced back to its place by the spring D, through the medium of the shoulder T on the latch-bar F bearing against the end of the plate P.
- 35 The tumblers N are each cut away at about the center, as seen at U, to permit of the passage through them of the tubular guide. The widths of these openings are exactly the same in every tumbler and about equal to the width of the key, as will be presently more fully explained.
- 40 The key represented at Fig. 5 is formed of sheet-steel, and has its extreme end cut and turned up at right angles to form a lip, a, which prevents its insertion in any but the proper manner. Wards equal to the number 45 of tumblers to be used in the lock are cut in opposite edges of the key-blank about equal to the thickness of the tumblers, the wards being out of line with each other to the same extent. Care is taken to have the distance between the 50 bottom of each ward and the projecting tongue opposite the same about equal to the width of the opening U in the tumblers. From this construction it will be observed that when the key is inserted and turned in the lock each ward 55 operates a different tumbler, throwing them alternately in different directions until the key has assumed a position at right angles to the plane of movement of the bolt, at which point of time the slots in the upper or front end of 60 the tumblers are all coincident and form a free passage for the entrance of the shoulder or stamp O of the bolt-plate P as it is retracted by the radial arm L as the rotation of the key is continued. The distance between the bottom 65 of the wards in the key and the opposite projecting tongues being about equal, as be-

fore stated, to the width of the openings U in the tumblers, and the tubular guide being formed with the rib I'', it follows that when the key is turned to something less than a right angle to the line of movement of the bolt all the tumblers are held perfectly rigid until the shoulder or stump O has obtained an entrance to the channel or gate in the upper end of the tumblers, thus doing away entirely with the necessity of all springs for accomplishing this result. The tumblers are brought back by the rib I'' on the tumbler-guide as the key is turned to withdraw it from the lock, and they then present a stop against which the end of the shoulder or stump O would come in contact, thus preventing the retraction of the bolt if an attempt is made to do so without the proper key.

It will be observed that to cut the slots in the end of the tumblers at the proper points 85 the key is first introduced and turned to something less than a right angle to the plane of movement of the bolt, when the end of each tumbler is marked at the point where the shoulder or stump O on the bolt touches the same, 90 when the slots are then cut at such points, and all subsequent movements of the key will bring the tumblers to exactly the same place.

I have shown my invention as applied to an ordinary night-latch, and the peculiarities in the construction of the bolt are simply the necessities of the combination, and I do not, therefore, wish to confine my invention to these features of construction, the gist of my invention resting in the idea of combining with the bolt 100 of a lock a series of tumblers cut away at about their center and adapted to allow the passage of the key through the same, the said openings being all made alike and of a width about equal to the width of the operative portion of 105 the key, so that the tumblers are positively held in position thereby. The notches and tongues of the key being opposite to each other, as shown, the tumblers are alternately vibrated in opposite directions, so that said tumblers 110 will be operated without the intervention of springs of any kind, and held perfectly firm and rigid by the key at the time that the lock-bolt begins its retraction, and unset by the rib on the tubular guide as the key is turned to 115 withdraw it.

I am aware that it is not new, broadly, to provide a flat key with a longitudinal rib to prevent false insertion, and that a projection has been formed by mortising a separate piece 120 to the key, and I do not wish to cover any such broad idea, my invention resting solely in the idea of forming the projection on the key by cutting the metal crosswise and turning up the lip so formed.

What I claim as new, and desire to secure by Letters Patent, is—

1. In a lock, a series of tumblers provided each with a gate at the front end and pivoted at their rear ends, and formed with central slots 130 or openings all of exactly the same dimensions and about equal in their shortest diameters to

the width of the operative portions of the key, in combination with the tubular guide I, whereby the tumblers are vibrated to bring the gates into line by the key and returned by the action

5 of the rib on the tubular guide, and without the intervention of any springs, substantially as hereinbefore set forth.

2. A flat sheet-metal key having its lower

end cut transversely and bent up to form a lip, substantially as and for the purpose set forth. 10

Witness my hand and signature this 9th day of October, 1879.

FREDERICK EGGE.

In presence of—

WARREN H. DAY,

HERMAN GAUSS.
